US00D945149S

(12) **United States Design Patent** (10) Patent No.: **US D945,149 S**
(45) Date of Patent: **** Mar. 8, 2022**

(54) **GUN HOLSTER**

(71) Applicant: **CYTAC TECHNOLOGY LIMITED**,
Shenzhen (CN)

(72) Inventor: **Yong Zhang**, Shenzhen (CN)

(73) Assignee: **CYTAC TECHNOLOGY LIMITED**,
Shenzhen (CN)

(**) Term: **15 Years**

(21) Appl. No.: **29/732,430**

(22) Filed: **Apr. 24, 2020**

(30) **Foreign Application Priority Data**

Nov. 5, 2019 (CN) 201930606304.6

(57) **CLAIM**

The ornamental design for a gun holster, as shown and described.

DESCRIPTION

FIG. 1 is a perspective view of a gun holster showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the gun holster where the gun holster is in a configuration of use.

The broken lines in the drawings depict portions of the gun holster, and additional environment matter in FIG. 9, that form no part of the claimed design.

1 Claim, 9 Drawing Sheets
